(57) **CLAIM**

The ornamental design for a tablet personal computer, as shown and described.

DESCRIPTION

FIG. 1 is a perspective view of a tablet personal computer showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is a perspective view showing the tablet personal computer of our design in use.
The broken lines shown in the drawings represent environmental structure and form no part of the claimed design.
